UNITED STATES PATENT OFFICE

113,183

DESIGN FOR A MOTOR PUMP VEHICLE

John J. Grybos, Elmira, N. Y., assignor to American-La France-Foamite Corporation, Elmira, N. Y., a corporation of New York

Application September 30, 1938, Serial No. 80,161

Term of patent 14 years

To all whom it may concern:

Be it known that I, John J. Grybos, a citizen of the United States, residing at Elmira, in the county of Chemung and State of New York, have invented a new, original, and ornamental Design for a Motor Pump Vehicle, of which the following is a specification, reference being had to the accompanying drawings, forming a part thereof.

Figs. 1 and 2 of the drawings are side and

rear views respectively showing the design in perspective.

The design of the far side of the pump vehicle is substantially the same as that of the near side illustrated in Fig. 1.

I claim:

The ornamental design for a motor pump vehicle, as shown and described.

JOHN J. GRYBOS.
